UNITED STATES PATENT OFFICE.

PETER HOBLER, OF CHICAGO, ILLINOIS.

DESIGN FOR A BASE FOR GRINDING-MILLS.

SPECIFICATION forming part of Design No. 18,698, dated October 23, 1888.

Application filed August 28, 1888. Serial No. 284,021. Term of patent 14 years.

To all whom it may concern:

Be it known that I, PETER HOBLER, of Chicago, county of Cook, and State of Illinois, have invented and produced a new and useful

- 5 Design for a Frame or Base for Portable Grinding-Mills, of which the following is a specification, reference being had to the accompanying drawing, forming a part thereof.

The figure in the drawing represents a perspective of my design, which consists of a supporting-frame of the form shown.

My design consists in a base or support, A, the inclined web-legs B B, and the step or journal-box C, supported on the upper joining 15 ends of said legs. The base A is nearly square in outline, the sides *a a* being a little rounding, while the sides *a' a'* have straight lines. This base is provided centrally with the enlarged opening *b*. The lower ends of the legs 20 or standards B B are widely extended and start upward from opposite sides of the opening *b*

and gradually curve inward and unite at the top, and are surmounted with the circular step-box C. The legs are arc-shaped in cross-section and have the central longitudinal ribs, *d d*. 25

What I claim as new is—

The design for a mill-frame or supporting-base, consisting of the base A, square in outline, or nearly so, and having a central opening, the arched legs B B, extending upward 30 from opposite edges of said opening and curving inward at the top and provided with the longitudinal ribs *d*, and the step-box C, uniting the upper ends of said legs and having the configuration shown and described. 35

In testimony whereof I affix my signature in presence of two witnesses.

PETER HOBLER.
